(57) **CLAIM**

The ornamental design for a blood pressure cuff and accessory set, as shown and described.

DESCRIPTION

FIG. 1 is a front view of a pressure cuff and accessory set; FIG. 2 is a front view thereof, shown in an alternate configuration;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken lines shown in the drawings are for the purpose of illustrating environmental features and portions of the blood pressure cuff and accessory set that form no part of the claimed design.

1 Claim, 7 Drawing Sheets
